COLLAR FOR SWEATERS

Louis C. Lerner, New Haven, Conn., assignor, by
mesne assignments, to Louis Lerner, New
Haven, Conn., and Abraham Lerner, Great
Neck, N. Y.

Application February 11, 1947, Serial No. 727,857

2 Claims. (Cl. 2—90)

1

The present invention relates to new and useful improvements in sweaters or similar garments and more particularly to a knitted collar for the garment constructed to present a square appearance.

An important object of the present invention is to provide a knitted collar for sweaters constructed from rectangular strips of material secured to the neck line of a sweater and shaping the neck to present a square appearance by forming tucks at the corners of the neck.

A further object of the invention is to provide a square neck for sweaters including a front and side portion of a single knitted strip of material and connecting the rear edges of the side portions by a back section of similar material.

A still further object is to provide an article of this character of simple and practical construction, which is neat and attractive in appearance, which may be manufactured at a relatively low cost and which otherwise is well adapted for the purpose for which it is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary front elevational view of a slip-on type sweater provided with a neck constructed in accordance with the present invention;

Figure 2 is a similar view of a coat sweater with the neck secured thereto;

Figure 3 is a fragmentary rear elevational view of the neck;

Figure 4 is a plan view of the strip of knitted fabric forming the front and sides of the neck;

Figure 5 is a similar view of the back section of the neck;

Figure 6 is a perspective view of the front and sides of the neck showing the tucks arranged to form the square neck, and

Figure 7 is a fragmentary sectional view taken substantially on the line 7—7 of Figure 6.

Referring now to the drawings in detail, wherein for the purpose of illustration I have disclosed a preferred embodiment of the invention, the numeral 5 designates a rectangular strip of knitted ribbed material having the spaced parallel ribs 6 extending transversely of the strip, one longitudinal edge of the strip being sewed to the front 7 and sides 8 of a square neck line of a garment 9, such as a sweater or the like.

As shown in Figure 1 of the drawings the gar-

2

ment 9 may comprise a slip-over type sweater while in Figure 2 the garment 10 may comprise a coat type sweater, both of said types of garments being provided with the square neck line.

5 The material 5 forming the front and sides of the neck of the garment is folded inwardly as shown at 11 at the corners 12 of the square neck line and sewed as at 13 at the inside of the neck to provide tucks 14. The seam 15 at the outer 10 surface of the tucks extends from the corner 12 of the neck line of the sweater toward the center of the neck to form a square neck opening 16 at the inner edges of the collar.

The rear edge of the collar is closed by a second 15 rectangular strip of knitted fabric 17 which is of a width substantially narrow with respect to the strip 5, the ends of the back strip 17 being secured to the rear edges of the side portions 18 of the collar and the lower longitudinal edge of 20 the strip 17 is sewed to the rear edge 19 of the neck line of the sweater.

The ribs 20 of the strip 17 likewise extend 25 transversely thereof and when the neck is secured in position to the garment the ribs all extend inwardly from the neck line of the garment to the neck opening 16 of the collar.

In applying the neck to the coat type sweater 30 the front section 20 of the neck is split in line with the edges of the front opening of the garment, the edges of the opening overlapping and the outer edge provided with a reinforcing strip 21 formed with buttonholes 22 to receive buttons 23 carried by the inner edge of the opening. Otherwise the necks for the two types of garments are constructed and secured to the garment in a similar manner.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a 45 preferred embodiment of the invention the same is susceptible to certain changes fully comprehended by the spirit of the invention as herein described and the scope of the appended claims.

What I claim is:

50 1. A collar for garments having a square neck line, said collar comprising a front section and a rear section both of rectangular shape, said front section being adapted to be secured by sewing along one longitudinal edge to the front and sides 55 of a neck line, tucks formed in said front section

at the front corners of the neck line and extending toward the center of the neck, and said rear section adapted to be secured by sewing along one longitudinal edge to the rear edge of the neck line and, the ends of the rear section being adapted to be secured to rear portions of the sides of the neck line, and portions of the front edge of the rear portion being sewn to the rear edges of the portions of the front section which are adapted to be secured to the sides of the neck line.

2. A collar for garments having a square neck line, said collar comprising a front section and a rear section both of rectangular shape and of knitted ribbed material, said rear section being substantially one-quarter the length of the front section and of less width than said front section said front section being adapted to be secured by sewing along one longitudinal edge to the front and sides of a neck line, tucks formed in said front section at the front corners of the neck line and extending toward the center of the neck, and said rear section adapted to be secured

5 by sewing along one longitudinal edge to the rear edge of the neck line, the ends of the rear section being adapted to be secured to rear portions of the sides of the neck line, and portions of the front edge of the rear portion being sewn to the rear edges of the portions of the front section which are adapted to be secured to the sides of the neck line.

10 LOUIS C. LERNER.
